UNITED STATES PATENT OFFICE.

GEORGE L. WINTERS, OF NEW YORK, N. Y.

SANITARY GARBAGE-CAN.

1,234,992.

Specification of Letters Patent. Patented July 31, 1917.

Application filed August 22, 1916. Serial No. 116,294.

To all whom it may concern:

Be it known that I, GEORGE L. WINTERS, a citizen of the United States, residing at New York, in the county of New York and State of New York, have invented certain useful Improvements in Sanitary Garbage-Cans, of which the following is a specification, reference being had therein to the accompanying drawing.

10 This invention relates to improvements in sanitary garbage cans, one object of the invention being the provision of a can in which the cover is provided with a disinfectant carrying means, so that the odor 15 from the garbage may be neutralized or entirely obliterated.

A further object of this invention is the provision of a device of this character which is simple, durable and inexpensive in construction, and thoroughly efficient and practical in use.

In the accompanying drawings:—

Figure 1 is a vertical central sectional view through a complete can, constructed according to and embodying the present invention.

Fig. 2 is a top plan view of the cover.

Fig. 3 is a bottom plan view thereof.

Referring to the drawings, the numeral 5 20 designates the can proper which may be made of any shape or size, and 6 indicates the cover.

This cover is provided with the two handles 7 by means of which the cover may be elevated.

Carried by the cover are the tubes 8, here shown in cruci-form formation, said tubes being provided with openings 9 therethrough and with a small tube 10 having a screw cap 11 for the reception of the disinfectant.

The disinfectant is then placed at the top of the can, and the openings 9 distribute the same so as to neutralize the odor of garbage from the can.

What I claim as new is:—

1. A cover for garbage cans, including a main body having extending diagonally thereon a cruci-form tubular member, said member being provided with perforations 50 therein, and a filling tube in communication with said member.

2. A cover for garbage cans, including a main body having extending diagonally thereon a cruci-form tubular member, said member being provided with perforations 55 therein, and a filling tube in communication with the cruci-form member at the center thereof.

In testimony whereof I affix my signature. 60

GEORGE L. WINTERS.
